UNITED STATES PATENT OFFICE.

JAMES FRYE, OF TORONTO, CANADA.

FLAP-FASTENER FOR BUTTON-SHOES.

SPECIFICATION forming part of Letters Patent No. 739,848, dated September 29, 1903.

Application filed January 23, 1903. Serial No. 140,238. (No model.)

To all whom it may concern:

Be it known that I, JAMES FRYE, of the city of Toronto, in the county of York, in the Province of Ontario, Canada, have invented 5 certain new and useful Improvements in Flap-Fasteners for Button-Shoes, of which the following is a specification.

My invention relates to improvements in flap-fasteners for boots or shoes; and the object of the invention is to devise a simple and durable form of fastener to be used in connection with each button of the shoe, whereby the use of button-hooks may be dispensed with and the flaps secured together; and it 15 consists, essentially, of a staple designed to coact with the stem of each button and fasten one fly of the flap and a plate on the other fly of the flap provided with a slot through which such staple is designed to extend when 20 the other fly of the flap is brought into position, such plate having also connected to it a button having a serpentine form of stem and the parts being arranged and constructed in detail, as hereinafter more particularly 25 explained.

Figure 1 is a perspective view of a shoe, showing the appearance of my buttons and fastening device. Fig. 2 is an enlarged perspective detail showing the flap separated. 30 Fig. 3 is a similar view showing the flaps fastened together. Fig. 4 is a cross-section showing the flaps connected together by my improved button-fastener.

In the drawings like letters of reference 35 indicate corresponding parts in each figure.

A is the underlying fly, and B the overlying fly, of the flap of an ordinary button-boot. The form of the flies forming the flap are of the ordinary construction.

40 C is a staple which extends through the plate c, such staple being suitably riveted to the inside of the fly A. The overlying fly B is provided with a plate D, having a slot d.

E is the button, which is provided with a 45 stem e of serpentine form, such stem having the loop portion e', which is held in position by the staple d', extending through the plate D to the inside of the fly and a loop e'', having a turned end e''.

50 It will be noticed that the stem e is made double in form and that the portion of the stem near the button is narrower than the

portion in which the loop e'' is formed and that the double sides of such loop extend, preferably, to the outside of the double narrower portion of the stem next the button. (See Figs. 2 and 4.)

When the flies are unfastened, the buttons are down in the position shown in Fig. 2; but when it is desired to fasten them they are 60 pulled in the direction indicated by arrow, so as to bring the fly B over the fly A, so that the staple C will pass through the slot d of the plate D. The button E is then thrown back into the position shown in Figs. 3 and 4, thereby 65 causing the loop e' to spring over and straddle the top bar of the staple C, and thus securely hold the button in position, as well as prevent the staple being thrown out of the slot d of the plate by any sudden jar. The 70 effect of any outward movement of the fly B would have a tendency more to hold the loop e'' in position by pressing on the loop e' of the stem, and it will thus be seen that the only means of undoing the buttons is to cant the 75 button into the position shown in Fig. 2, thereby bringing the loop e'' out of engagement with the bar of the staple C. It will of course be understood that the loop e'' is close together at the mouth, and the turned edge e'' 80 as well as the loop e', serves to form a mouth, so as to readily guide the staple C into position in the loop.

What I claim as my invention is—

1. In a button boot or shoe the combination 85 with the under fly having a staple extending up from the outer face thereof, of an over fly having a slot through which the staple is designed to extend, and a button pivotally attached to the upper face of the fly in proximity to the slot and having means for engaging the portion of the staple projecting through the slot, substantially as described.

2. In a button boot or shoe the combination 95 with the under fly having a staple extending upward from the outer face thereof of the over fly having a slot therein, a plate secured to the outer face of the over fly having a slot aligning with the slot in the fly and a button pivotally connected to the plate and having means for engaging the portion of the staple projecting through the slot, substantially as described.

3. In a button boot or shoe, the combination

with the under fly and staple extending therefrom, of the over fly having a slot through which the staple is designed to extend, and a button having a serpentine stem formed 5 with a double loop, a staple for fastening the stem by one of the loops to the outer fly, and the free loop of the stem being adapted to be passed over the staple extending through the slot as and for the purpose specified.

10 4. In a button boot or shoe, in combination the under fly, the staple and plate suitably fastened to the same, the outer fly, the plate

fastened to the same and provided with a slot, the button having a double stem with a double loop, a staple extending through the plate 15 and fastening the inner loop in position, and the outer loop being designed to extend over the staple and secure the button and staple in position substantially at right angles to the flap as and for the purpose specified.

JAMES FRYE.
